UNITED STATES PATENT OFFICE.

FRANZ F. ZIEGLER, OF PROVIDENCE, RHODE ISLAND, ASSIGNOR TO DAVOL RUBBER COMPANY, OF PROVIDENCE, RHODE ISLAND, A CORPORATION OF RHODE ISLAND.

DESIGN FOR A HOLLOW RUBBER FIGURE TOY.

52,200.

Specification for Design.

Patented July 16, 1918.

Application filed April 28, 1917. Serial No. 165,278. Term of patent 14 years.

To all whom it may concern:

Be it known that I, FRANZ F. ZIEGLER, a subject of the Emperor of Germany, residing at Providence, in the county of Providence and State of Rhode Island, have invented a new, original, and ornamental Design for Hollow Rubber Figure Toys, of which the following is a specification, reference being had to the accompanying drawings, forming part thereof.

Figure 1 is a front view of the figure toy, showing my design, and

Fig. 2 is a back view of the same.

I claim:

The ornamental design for a hollow rubber figure toy, as shown.

FRANZ F. ZIEGLER.

Witnesses:

ADA E. HAGERTY,
J. A. MILLER.
